UNITED STATES PATENT OFFICE

JOHN J. TATUM, OF BALTIMORE, MARYLAND

STAKE POCKET

Application filed October 5, 1929. Serial No. 397,654

In railroad cars the stake pockets which are most commonly used are rigid; that is to say, they are, as a rule, made of metal bars bent in substantially U shaped form and 5 bolted or riveted to the car, and constitute a rigid projection within the car which is objectionable in that they present obstructions in loading a car when the stakes are not in use, and it frequently happens that in loading 10 the car with heavy lading pieces of lading strike these pockets and distort them to such an extent that it is impossible to place a stake in them.

The primary object of my invention is to 15 provide a folding stake pocket that will give a maximum of efficiency, and a maximum of clearance in the car on which it is used. A further object of my invention is to provide a folding stake pocket of such construction 20 that the liability to damage it by lading is reduced to a minimum, and with these and other objects in view my invention consists of the parts and combination of parts as hereinafter pointed out.

25 In the drawings:

Figure 1 is a front elevation of my improved stake holder attached to a car wall with the loop up in operative position.

Figure 2 is a top plan view of Figure 1.

30 Figure 3 is a side elevation of Figure 1.

Figure 4 is a detail view of another embodiment of my invention.

Figure 5 is a front elevation of another embodiment of my invention.

35 Figure 6 is a top plan view of Figure 5.

Figure 7 is an end elevation of Figure 5.

Figure 8 is a front elevation of another embodiment of my invention.

Figure 9 is a top plan view of Figure 8.

40 Figure 10 is a side elevation of Figure 8.

Referring now to Figures 1 to 3, the reference numeral 11 designates the car wall, and this numeral will be used in all of the figures of the drawings to designate the car wall.

My improved stake pocket or holder comprises two side brackets 12 provided intermediate their ends with a substantially U shaped bearing or keeper 13. These brackets 45 are designed to be rigidly secured to the car

wall at their lower ends by rivets or bolts 14. The upper end portions of the brackets are provided with enlarged or elongated bolt, or rivet openings 15, adapted to receive the rivets or bolts 16. It will be noted 55 that the distance between the heads of the rivet 16 is greater than the combined thickness of the car wall 11 and bracket 12 so that, as shown in Figure 3, there is a clearance between the rivet head and the upper 60 end portion of the bracket which permits of the upper end of the bracket being sprung outward from the car wall and the upper wall of the bearing being sprung a greater distance away from the lower wall thereof, 65 to permit expansion and subsequent contraction of the bearing, as will be hereinafter more fully explained.

The upper arm of the keeper or bearing 13 is provided with an offset or shoulder 17. It 70 will be noted that the vertical dimension of the bearing is less than the width of the trunnion of the loop, as will be hereinafter explained.

The stake holding loop 18 is in this embodiment, preferably, made of flat metal and its trunnions 19, 20, are rectangular in cross section and of less width than the balance 75 of the loop. In this connection it will be noted from Figure 3 that the vertical dimension of the bearing 13 is slightly less than the width of the trunnions 19, 20, except immediately adjacent the car side, where it is slightly more, which results in the formation of the shoulder 17.

As the loop 18 is raised to the full line position shown in Figures 1 and 3 to receive the stake 21, in which position it stands outwardly from the car wall, the trunnions 19 and 20 fulcruming on the lower wall of the bearing 13 move the upper wall of the bearing with the upper end portion of the brackets (which action is permitted by the enlarged bolt opening 15) and continued upward movement of the loop rotates the trunnions back 85 of the shoulders 17 which hold the loops in operative position to receive the stake 21.

In the event that the loops are left in elevated position, after the stake has been removed, it will not be damaged by lading fall- 100

ing on it, because a blow or weight on the loop will result in it moving on its trunnions and folding against the car wall.

Referring to Figure 4, it will be seen that I provide the bearing 13a of the bracket with a recess or seat 22, adapted to receive and lock the trunnions of the loop 18a and hold the loop in elevated position. This form of bracket may be used when desired in place of that shown in Figs. 1, 2 and 3, or the seat 22 may be added to the bracket shown in Figs. 1, 2 and 3.

The embodiment shown in Figures 5 to 7 comprises the stake loop 18b having its free ends 23 and 24 turned outward to form trunnions which are mounted for rotation in the brackets 25, 26, secured to the car wall. In this embodiment and in all embodiments of my invention the stake loop is made flat to give a broad extended bearing surface for the stake, thus reducing wear on the stake.

In Figures 5 to 7 the trunnions 23 and 24 are substantially square in cross section as shown in Figure 7 with its corners slightly rounded. The brackets 25 and 26 are secured at their lower ends to the car by suitable means 26a, while the upper end of these brackets are held to the car by means of the rivets or bolts 26b, said upper end portions being provided with elongated slots 26c, through which the rivets 26b pass. The brackets are provided with bearings 30 in which the trunnions 23 and 24 are journaled. The rectangular cross section of the journals 23 and 24 function to hold the loop 23a either in its adjusted up or down position, and in order to permit the brackets to flex when the journals are turned in their bearings I provide the elongated slot 26c which permits the upper end portion of the brackets to slide or spring relatively to the rivet 26b, as will be understood.

In Figures 8, 9, 10, I have shown another embodiment of my invention. In these figures the brackets 32 are provided with the trunnion bearings 34, the inner edges of which are provided each with a notch 35 terminating at its lower end in a cam face 36. The loop 37 has the trunnions 38, and the side arms of the loop are of greater diameter at their inner end portions as at 39. The side arms of the loop 37 are under a spring tension when the loop is mounted in the brackets, so that when it is raised to receive the stake the enlarged portions 39 spring into the recesses or notches 35, thus holding the loop in elevated position.

As the loop is raised or lowered the portion 39 is guided to and from the notch 35 by the cam face 36, so that in lowered position the portions 39 are forced in close frictional contact with the inner edges of the brackets and the loop held against accidental movement.

As will be seen from the several embodiments of my invention there is a spring reten-

tion action between the brackets and the loops whereby the loops are firmly held in adjusted positions. If, per chance the stake is removed from the loop and the operator fails to fold the loop down against the car side there is no danger of the loop becoming distorted because if lading is loaded on the car, while the loop is up and without a stake in it, and the lading strikes the loop the loop will on such impact swing on its trunnion and fold against the side of the car.

What I claim is:

1. In a folding stake pocket, brackets, bearings on said brackets, a stake holding loop having trunnions mounted in said bearings and normally held against rotation therein, and a yieldable connection between the bearings and car yieldable under pressure of the trunnions, whereby the loop is allowed to turn for movement to a folded position.

2. In a folding stake pocket, supporting brackets, and a stake loop mounted on said brackets, said loop embodying a part under spring tension and engaging a bracket to support the loop in an adjusted position.

3. A stake pocket comprising a bar having trunnions of rectangular cross-section pivotally mounted in yielding bearings on the side of a vehicle.

4. A stake pocket comprising a bar having trunnions of rectangular cross-section rotatably mounted in yielding bearings on the side wall of a vehicle.

5. A stake pocket comprising bearings at the sides of the pocket adapted to be secured to the wall of a car, said bearings having resilient portions, and a stake holding element provided with trunnions rotatably engaging the bearings and normally held frictionally thereby to retain the element in an active position, said trunnions being operative to act on said resilient portions to decrease their frictional hold on the trunnions under a predetermined pressure on the element to permit the latter to turn to an inactive position.

6. A stake pocket comprising bearings at each side of the pocket adapted to be secured to the walls of a car, and a stake holding element having trunnions engaging the bearings, at least one of the bearings having a resilient portion and the coacting trunnion having a surface for engagement therewith to normally hold the element in an active position, the said surface of the trunnion being operative on the application of predetermined pressure to the element to move said resilient bearing portion to release the element to permit the same to move to an inactive position.

7. A stake pocket comprising bearings at each side of the pocket adapted to be secured to the wall of a car, and a U-shaped stake holding element having its arms provided with trunnions rotatably engaging said bearings, the bearings and element having sur-

faces resiliently engaged to normally hold the element in an active position and adapted under a predetermined pressure upon the element to reduce the frictional engagement and thereby permit the element to move to an inactive position.

8. A stake pocket comprising bearings at each side of the pocket adapted to be secured to the wall of a car, and a U-shaped stake holding member having its arms provided with trunnions rotatably engaging the bearings, said element being rotatable in a vertical plane on the bearings and held against lateral motion thereby, the bearings having resilient surfaces for frictional engagement with the element whereby to hold the element in an active position and operable on a predetermined pressure on the element to reduce the frictional engagement and permit said element to move to an inactive position.

9. In a stake pocket, the combination with a car wall, of bearings on the car wall, and a stake holding element having trunnions mounted in the bearings and frictionally engaged therewith to hold the stake holding element in an adjusted position and against rotation, said bearings being connected with the wall for yielding movement to reduce the friction on the trunnions and thereby permit the stake holding element to be rotated.

10. A stake pocket comprising bearings at each side of the pocket, and a stake holding element rotatably engaging said bearings and held under spring pressure thereon in active position and adapted under a pressure greater than such spring pressure to swing to an inactive position.

11. In a collapsible stake pocket, the combination, with a vehicle, of a bearing at each side of the pocket secured to a wall of the vehicle so as to permit expansion and contraction of said bearing, and a stake holding element having trunnions rotatable in the bearings and normally held in an adjusted position in a contracted condition of the bearings, said bearings being adapted to expand under pressure of the trunnions in a rotary motion of the latter to permit said trunnions to have such motion.

12. In a collapsible stake pocket, bearings at the sides of the pocket, and a stake holding element having trunnions rotatable in the bearings, said bearings normally resisting rotary motion of the trunnions and being expansible under a predetermined pressure of the bearings to permit of such motion thereof.

13. In a collapsible stake pocket, the combination, with a car, of brackets provided with bearings, said brackets being fixedly secured at their lower ends to the wall and loosely secured at their upper ends to the wall to permit the upper portions of the bearings to have spreading motion relative

to the lower portions thereof, and a U-shaped stake retaining element having its arms provided with trunnions engaging said bearings, said trunnions being formed to be frictionally held by the bearings to retain the element in active position and adapted, under a predetermined pressure on the bearings, to spread the bearings to permit the element to swing to an inactive position.

14. In a collapsible stake pocket, the combination, with a car, of brackets provided with bearings, said brackets being fixedly secured at their lower ends to the wall and loosely secured at their upper ends to the wall to permit the upper portions of the bearings to have spreading motion relative to the lower portions thereof, and a U-shaped stake retaining element having its arms provided with trunnions rotatably engaging said bearings, said trunnions being of angular shape in cross-section and normally adapted for frictional engagement with the bearings to hold the element in an active position and operative, under a predetermined pressure on the element, to spread the bearings to permit said element to swing to an inactive position.

15. In a collapsible stake pocket, the combination, with a car, of brackets provided with bearings, said brackets being fixedly secured at their lower ends to the wall and loosely secured at their upper ends to the wall to permit the upper portions of the bearings to have spreading motion relative to the lower portions thereof, and each bearing having an offset portion forming a keeper recess, and a U-shaped stake holding element having its arms provided with trunnions rotatably engaging the bearings, said trunnions being formed for interlocking engagement with the keeper recesses to hold the element in an active position and adapted, under a predetermined pressure on the element, to spread the bearings and release the element and permit said element to swing to an inactive position.

In testimony whereof I affix my signature.
JOHN J. TATUM.
